UNITED STATES PATENT OFFICE.

JEAN PIERRE FONTAINE, OF PARIS, FRANCE.

PRIMARY ELECTRIC BATTERY.

SPECIFICATION forming part of Letters Patent No. 670,583, dated March 26, 1901.

Application filed January 9, 1900. Serial No. 848. (No model.)

To all whom it may concern:

Be it known that I, JEAN PIERRE FONTAINE, doctor of medicine, a citizen of the République of France, residing at Paris, in the République of France, (whose post-office address is 36bis, Rue Ballu, Paris, aforesaid,) have invented a certain new and useful Improved Primary Electric Battery, (for which application for a patent has been made in France, dated the 3d 5 of October, 1899; in Germany, dated the 18th day of December, 1899, and in England, No. 25,011, dated the 16th day of December, 1899,) of which the following is a specification.

This invention has for its object the application to electric batteries, by means of different porous vessels, of improved combinations of substances which react one upon the other under such conditions that their electric actions jointly or combined result in producing what may be called a "double excitation" and yield a voltage superior to those hitherto obtained.

It is well known that the Becquerel battery is constituted of two solutions, the one acid (nitric acid) and the other alkaline, (potash,) reacting one on the other through a porous vessel. The electricity produced by this reaction is taken to the external circuit by two strips of platinum, one immersed in the acid 25 and the other in the alkaline solution. After numerous experiments it has been found preferable to replace the strip of platinum immersed in the potash by zinc, the oxidation of the zinc coming to the aid of the reaction 30 of the nitric acid on the potash. On the other hand, the strip of platinum immersed in the nitric acid is replaced by carbon.

In consequence of modifications which by this invention have been introduced in the 40 Becquerel battery I have been able to obtain a tension of 2.55 volts by utilizing nitric acid of 36° Baumé. Hitherto not more than 2.20. volts have been obtained. Instead of nitric acid at 36° Baumé a mixture of nitric and 45 sulfuric acids, diluted with water in the proportion of four volumes of nitric acid at 36°, one volume of sulfuric acid, and five volumes of water, may be employed. With this mixture the voltage obtained is only 2.35 volts. 50 Nevertheless the result must still be considered as very good. It has also been found

that the double excitation was not peculiar to the combination of zinc, potash, and nitric acid, but that it could also be realized by replacing, under the same conditions as hereinbefore, the soda solution by a solution of chlorid of sodium of thirty per cent. This second combination with the object of producing the double excitation yields two volts with nitric acid at 30° Baumé and 1.80 volts 55 with the mixture of nitric and sulfuric acids diluted in water.

In the first combination of zinc, soda, and nitric acid or a mixture of nitric and sulfuric acids diluted in water oxidation of the zinc 60 finishes by forming zincate of soda, the hydrogen arising from this reaction being absorbed by a fraction of the oxygen of the nitric acid. On the other hand, the unreduced nitric acid and the sulfuric acid react on the 65 soda to form nitrate and sulfate of soda. In the second combination of zinc, chlorid of sodium, and a mixture of nitrate and sulfuric acids diluted in water there is also a formation 70 of nitrate and sulfate of soda with a release of chlorin, which attacks the zinc and forms chlorid of zinc. Another fraction of the chlorin combines with the hydrogen arising from the decomposition of the water and produces hydrochloric acid and the remainder 75 escapes mixed with the nitrous vapors arising from the reduction of a certain quantity of nitric acid by the hydrogen unabsorbed by the chlorin. Without being able to affirm the exactness of these reactions it 80 is believed that the explanation of them is correct. The proportions in which the mixture of nitric and sulfuric acids is diluted with water may also be increased while still 85 preserving a very good return.

The arrangements which are now adopted in this invention for making use under the best possible conditions of the effects hereinbefore recited will now be described.

In the accompanying drawings, Figure 1 is 90 a vertical section through the center of my improved battery. Fig. 2 is a section, partly in plan, on the line X X of Fig. 1. Fig. 3 is a vertical section through the axis of a battery in modified form. Fig. 4 is a horizontal 95 section on the line y y of the preceding figure.

This double-excitation battery comprises:

First, an external vessel 1 of glass or other suitable substance.

Second, a piece of zinc immersed in the external liquid which may be a solution of soda, 5 potash, or chlorid of sodium. This zinc is shown as having the form of a sleeve 2, and it is suspended from the lid or cover by means of screwed rods 3 of copper having terminal nuts. These rods are carefully coated with 10 india-rubber or a mixture of india-rubber and paraffin not only along all their length, but also at their point of attachment to the zinc. For certain purposes the formation of the piece of zinc as a tube is not advisable and it 15 is preferable to substitute therefor simple plates or rods of zinc.

Third, a porous vessel. This porous vessel having to be interposed between an acid solution and an alkaline solution must therefore 20 have a composite wall, the porous substance most suitable for acids—that is to say, glazed earthenware—not being always the best when exposed to alkaline lyes, which attack it and rapidly destroy it. The wall of the 25 porous vessel is composed from the outside to the inside, first, of a cardboard-piece 4, rolled or wrapped with fabric 5 and in contact with the soda solution, and then a layer of porous earthenware 6 or porous carbon. This second 30 part of the vessel is in contact with the acid. Its filtering action on this liquid is usefully added to the same action of the cardboard on the alkaline lye for regulating and moderating the chemical actions of the battery, which 35 would be far too active if a single vessel of cardboard and canvas were utilized. The earthenware or carbon also at the same time imparts rigidity to that part of the vessel which otherwise would be liable to become 40 deformed under handling, particularly in the case of large batteries. In case carbon is employed in preference to earthenware it may serve at the same time as one electrode. The porous vessel thus formed is also suitable for 45 the combination of chlorid of sodium and nitric acid. For little batteries the porous earthenware vessel must be comparatively very small, and in view of the difficulty of making an earthenware vessel having walls 50 sufficiently thin it may be replaced by a diaphragm of hardened cardboard, ebonite, celluloid, or other suitable material. This diaphragm, which is not shown in the drawings, is perforated with holes greater or less in size 55 and more or less numerous, according to the intensity which it is desired to have in the chemical action.

Fourth, a carbon, which is preferably a hollow cylinder 9, as shown in the drawings, 60 Figs. 1 and 2. This cylinder is prolonged to the outside of the vessel in the form of a shank 10, on which the terminal is fixed for taking the positive pole of the current. The cylinder is bored with holes 11 or has four slots 12 65 at ninety degrees on its lower part, or the carbon may be a simple plate 20, as shown in

Figs. 3 and 4, with the rods 21 for suspending the naphthalene extending horizontally through the plate and forming a support for the naphthalene.

The naphthalene that is placed above the compartment containing the nitric acid and which has for its object the absorption of the electric or chlorin fumes is sustained by a suitable support placed over the nitric-acid 70 compartment. The form which I preferably employ for constituting this support is as follows: As may be seen in section in Fig. 1 and in plan view in Fig. 2, the carbon cylinder is traversed toward two-thirds of its height by pins 14, placed sufficiently closely together to support the pieces of naphthalene 7, and the number of the pins is in proportion to the size of the battery. A ring 13, of carbon or any other insulating material, (celluloid, hardened cardboard, ivorin, or the like,) is placed on the outside of the carbon cylinder 9, surrounding the said cylinder and resting with its lower part on the pins 14. The external surface of the ring 13 is entirely in contact with 80 the porous vessel. Its internal surface is in communication with the external wall of the cylindrical carbon only by its lower portion. The upper portion of the ring is constituted by a very thin wall, which allows, consequently, a space between it and the carbon, and this free space is also filled with pieces of naphthalene 7. In any case it must be understood that instead of causing the pieces of naphthalene to be supported on the pins 14, 90 hereinbefore described, I may simply place them in a perforated porcelain vessel placed above the nitric acid. To the naphthalene there may be added potash and baryta; but this is not necessary.

The arrangements hereinbefore described have among other advantages that of rendering these batteries easily transportable, the substances utilized for absorbing the nitrous vapors preventing the liquid in the interior of the porous vessel from being spilled. In order to prevent the soda in the external vessel escaping in consequence of shakings or the inclination of the battery, a thin layer of linseed 8, which renders the surface of the liquid 100 stationary, is placed on the surface.

Fifth, a lid or cover 16, of hardened cardboard or of iron coated with a mixture of gutta-percha and paraffin. The lid 16 is provided with a flange which fits close to the internal wall of the glass vessel and gives a more perfect tightness, which is also increased by the addition of a ring or flange of india-rubber 17, which engages over the periphery of the lid and the rim or bead which terminates the upper edge of the glass vessel.

I declare that what I claim is—

1. A double fluid battery having active elements consisting of zinc, and of soda-lye on the one hand and nitric acid on the other hand in combination with a porous vessel of cardboard and fabric placed together and 130

having a rigid internal substance permeable by the acid solution, substantially as described.

2. A double fluid battery having active elements consisting of zinc, and of soda-lye on the one hand and nitric acid on the other hand, in combination with a porous vessel of cardboard and fabric placed together and having a rigid internal substance permeable by the acid solution and a perforated vessel above the nitric acid containing naphthalene for absorbing the nitrous vapor.

3. A double fluid battery having active elements consisting of zinc, and of soda-lye on the one hand and nitric acid on the other hand in combination with a porous vessel of

cardboard and fabric placed together and having a rigid internal substance permeable by the acid solution, a perforated receptacle above the nitric acid containing naphthalene for absorbing the nitrous vapors and a layer of linseed above the soda-lye for rendering stationary the surface of the soda-lye, substantially as described.

In witness whereof I have hereunto signed my name, this 21st day of December, 1899, in the presence of two subscribing witnesses.

JEAN PIERRE FONTAINE.
